(57) **CLAIM**

The ornamental design for a physical therapy belt controller, as shown and described.

DESCRIPTION

FIG. 1 is a first perspective view of a physical therapy belt controller showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is the combined use state of FIG. 1.

The broken lines shown in the drawings illustrate portions of the physical therapy belt controller that forms no part of the claimed design.

The additional broken lines in FIG. 9 illustrate environment and forms no part of the claimed design.
